DESIGN.

No. 35,617.

C. DESORMOUX.

URINAL.

(Application filed Dec. 21, 1901.)

Patented Jan. 28, 1902.

UNITED STATES PATENT OFFICE.

CHARLES DESORMOUX, OF CLEVELAND, OHIO.

DESIGN FOR A URINAL.

SPECIFICATION forming part of Design No. 35,617, dated January 28, 1902.

Application filed December 21, 1901. Serial No. 86,858. Term of patent 7 years.

To all whom it may concern:

Be it known that I, CHARLES DESORMOUX, a citizen of the United States of America, residing at Cleveland, in the county of Cuyahoga and State of Ohio, have invented and produced a new and original Design for Urinals, of which the following is a specification, reference being had to the accompanying drawings, forming part thereof.

Figure I is a view in perspective of a urinal, showing my design, and this figure shows the top, the front, and the right-hand side of the urinal. Fig. II is a left-hand side elevation. Fig. III is a front elevation.

My new design for a urinal comprises an oval-shaped or ovaloid rim *a*, formed upon and around the upper end of the urinal. The rim *a* is rounded on top.

The exterior surfaces *b* of the upper portion of the front and forward portions of the upper ends of the sides of the urinal recede or slope, as at *b*, inwardly and downwardly from next below the rim *a*.

The rear portion *c* of the upper end of each side of the urinal is convex or bulges laterally and outwardly, as at *c*. The convex or bulging portions *c* of the sides of the urinal are gradually enlarged in width toward the rim *a*.

The urinal extends considerably below its upper outwardly-bulging portions *c*, and the sides of the urinal below the bulging portions *c* are flat and perpendicular or approximately perpendicular, as at *d*, and each side next forward of its bulging portion *c* has a flat and perpendicular or approximately perpendicular surface *e*, which forms an upward extension of the straight and flat surface *d* of the said side.

The front of the urinal next below the sloping surface *b* of the said front is flat and perpendicular or approximately perpendicular, as at *f*.

At the rear of the upper end of the urinal and contiguous to the rim *a* appears a rearwardly-projecting member *h*.

A flange *k* is formed upon and around the lower end of the urinal, and the said flange swells or curves outwardly, as at *l*, where its forward edge joins the side edges of the flange, and the said edges curve inwardly, as at *m*, along their central portion.

The leading and characteristic and essential features of my design comprise the oval-shaped or ovaloid rim *a*, appearing upon the upper end of the hopper, the laterally and outwardly bulging or convex upper portions *c* of the sides of the hopper, the flat and straight surface *f* of the front of the hopper, and the flat and straight surfaces *d* of the sides of the hopper below the bulging portions *c* and with the said surfaces *d* extended, as at *e*, upwardly and forwardly of the bulging portions *c*.

What I claim is—

The design for a urinal substantially as herein shown and described.

In testimony whereof I sign the foregoing specification, in the presence of two witnesses, this 16th day of December, 1901, at Cleveland, Ohio.

CHARLES DESORMOUX.

Witnesses:

C. H. DORER,
VICTOR C. LYNCH.
